UNITED STATES PATENT OFFICE.

WILLIAM J. MARTIN, OF BUFFALO, NEW YORK, ASSIGNOR OF ONE-HALF TO FRANCIS J. CARR, OF BUFFALO, NEW YORK.

INTENSIFIER.

1,037,031.

Specification of Letters Patent. Patented Aug. 27, 1912.

Application filed September 2, 1909. Serial No. 515,887.

To all whom it may concern:

Be it known that I, WILLIAM J. MARTIN, a citizen of the United States, residing at Buffalo, in the county of Erie and State of New York, have invented certain new and useful Improvements in Intensifiers, of which the following is a specification.

My invention relates to an air-controlled intensifier adapted to inject a quantity of oil against a movable body under a greater pressure than that of the air used to actuate the same.

The primary object of my invention is the production of a simple and effective device of this character particularly adapted for use in connection with car-door locks and to so construct the device that the air in the air-brake system acts upon the intensifier and actuates the same to force a quantity of oil against a movable body or piston controlling the locking-mechanism of a car-door lock, the pressure against said movable body or piston being considerably greater than the pressure of the air used to manipulate the intensifier.

Another object of my invention is to combine with this intensifier, an inlet-valve provided with a tumbler and to so construct the manipulating parts that a series of different movements will be required before air can be introduced into the intensifier, thus avoiding manipulation of the intensifier and its co-acting inlet-valve by uninstructed parties.

With these and other objects in view, my invention consists in the construction, arrangement, and combination of parts to be hereinafter described and particularly pointed out in the subjoined claims.

In the drawings.—Figure 1 is a side elevation of my intensifier showing the manner of attaching the same to a freight car equipped with a pressure-actuated door-lock. Fig. 2 is a central longitudinal section through the intensifier, the inlet-valve co-acting therewith, and the lower end of a pressure-actuated car-door lock. Fig. 3 is a plan view of the inlet end of the intensifier. Fig. 4 is an enlarged section of the inlet-valve taken on line 4—4, Fig. 2. Figs. 5 and 6, are vertical longitudinal sections through the inlet-end of the intensifier showing the parts in different positions than shown in

Fig. 2. Fig. 7 is a transverse section taken on line 7—7, Fig. 2.

Referring now to the drawings in detail, like letters of reference refer to like parts in the several figures.

The intensifier considered as a whole is designated by the letter A and the inlet-valve co-acting therewith by the letter B; said valve being secured to the car C and having a supply-pipe B¹ connected thereto which leads to the air-brake system of the car.

D designates a portion of a power-controlled car-door locking-mechanism, such as was patented to me March 2, 1909, and numbered 913,834. It is my intention to arrange the car-door locking-mechanism so that it requires a pressure of upward of 200 pounds per square inch to manipulate the same; and as the primary power-agency employed to manipulate said locking-mechanism is diverted from the air-brake system, which is usually under a pressure of less than 80 pounds per square inch, my improved intensifier is interposed between the locking-mechanism and the air-brake system.

The locking-mechanism comprises a tube or casing E having a bushing E¹ closing the lower end and provided with a winding passage e and with depending flanges e¹ having inwardly-directed portions e² whose upper faces are inclined for a purpose to appear hereinafter; said flanges e¹ and inwardly-directed portions e² constituting one member of a coupling.

The inlet-valve B comprises a casing b closed at its upper end by a cap b¹ having a central pocket b² in which is located a coil-spring b³ acting against the upper end of a valve F normally seated against a valve-seat formed in a removable seat-disk F¹ threaded into the casing b. Coincident with said valve-seat is an air-passage f through which the lower reduced end f¹ of the valve F extends; said lower reduced end being somewhat smaller in diameter than the air-passage f in the disk F¹ so that when the valve F is unseated, the air may pass through said disk. The disk F¹ is seated against a shoulder f² formed by reducing the internal diameter of the valve-casing beneath the disk F¹. A second reduction of the internal diameter of the valve

casing is made to form a shoulder f^3 against which bears a lifting-disk G of somewhat smaller diameter than the diameter of the valve-casing between the shoulders f^2 and f^3 so that an annular intervening space is provided between the valve-casing and the edge of said disk. A coil-spring F² is located centrally within the casing and bears at opposite ends against the disk F¹ and G 10 and as the disk F¹ is held against movement by reason of its being threaded into the valve-casing, said spring acts to retain the lifting-disk G against the shoulder f^3 . A further reduction in the internal diameter 15 of the valve-casing is made at its lower end to provide a shoulder g against which a tumbler-disk H bears; said disk being of somewhat smaller diameter than the internal diameter of the valve-casing between the shoulders f^2 and g, and between the disks H and G a coil-spring G¹ is interposed; said spring being less powerful than the spring F² so that the disk H may be forced upward in the valve-casing without causing the lifting-disk G to become unseated. Spring G¹ 20 serves to retain the tumbler-disk H in contact with the shoulder g of the valve-casing. The lifting-disk G is provided with depending lugs g¹, see Fig. 7, and the disk H with an upstanding lug h adapted to strike the underside of the disk G when the disk H 25 is elevated and the upperside of the latter is adapted to come in contact with the lugs g¹ on the disk G so that after the coil-spring G¹ is compressed and the lugs h and g¹ come 30 in contact with their coöperating parts, disk G may be forced up into the casing against the action of the coil-spring F².

In order to prevent manipulation of the 35 valve B except by a specially designed part of the intensifier, the tumbler disk H is provided on its underside with two depending lugs h¹ and it also is provided with a marginal notch h², see Figs. 4 and 6, adapted 40 to pass over a lug b⁴ formed on the inner side of the valve-casing. Said notch, however, is normally held out of line with the lug b⁴ so that the disk H must be given a slight rotary movement to bring the marginal notch h² in line with the lug b⁴ and not 45 until this relation is brought about can the tumbler-disk H be elevated.

The intensifier proper comprises a cylindrical casing I provided with two cylindrical tubes i, i², arranged at right-angles thereto and adapted for connection, respectively, with the lower end of the bushing E¹ of the locking-mechanism and with the valve B. Each of said tubes is reduced 50 between its ends, as at i³, and fitting onto each of said reduced portions, is a coupling-member J. The coupling-member held on the tube i, which I will term the outlet-tube, is provided with a pair of outstanding segmental flanges j adapted to engage the in-

wardly-directed portions e² at the lower end of the flanges e¹ depending from the bushing E¹ of the locking-mechanism. Said coupling is rotatable on the outlet-tube so that its outstanding flanges j may pass upward 70 between the inwardly-directed portions e² of said bushings and upon giving said coupling member a partial rotation, said flanges j will ride on the inclined upper faces of the portions e² and thus crowd the tube upward against the underside of the bushing E¹. In order to assure a tight connection between the bushing and said tube so as to prevent leakage of oil at this point, the outer end of the tube is faced with a gasket j¹. 75

The coupling J held onto the tube i², which I will term the inlet-tube, has inwardly-directed segmental flanges j² which are adapted to engage the inclined upper 85 sides of outstanding lugs b⁵ formed at the lower end of the valve-casing, the flanges j² being adapted to pass between the spaces separating the lugs b⁵ and upon a partial rotation of the coupling will ride over the 90 inclined faces of said lugs and cause the tube i² to be forced against the lower end of the valve casing. The inlet-tube i² also has a gasket at its outer end adapted to bear against the lower end of the valve-casing 95 and prevent the escape of air at this point.

The cylindrical body I of the intensifier has a small bore K and a comparatively large bore K¹, the small bore K being in communication with the outlet-tube i, while 100 the bore K¹ is in communication with the inlet-tube i². Opposite ends of the cylindrical body I are closed with screw-plugs L or in any other suitable manner. Arranged to reciprocate within the bore K¹ is a piston K² having connection by means of a rod k with a smaller piston K³, adapted to reciprocate in the bore K. The normal position of the pistons K² and K³ is that shown in Fig. 2, at or near the right hand end of 110 their respective bores. The bore K is filled with oil or other suitable liquid which is adapted to be forced out through the outlet-tube i, through the winding passage e in the bushing E¹, and into the tube or casing E of the car-door lock. Said oil acts against a piston or other movable body M, which in turn acts against a locking-plunger m adapted to interlock with the car-door. 115

The air from the air-brake system is introduced into the intensifier through the inlet-tube i² and acts against the piston K², forcing the same to the left in Fig. 2, and by reason of the piston K³ being rigidly connected with piston K² and being of smaller 125 diameter, the oil within the bore K is forced against the piston or movable body M in the casing E with increased pressure.

For the purpose of opening the valve F within the valve-casing b, a tube N is pro- 130

vided which extends diametrically through the body I of the intensifier and axially through the inlet-tube i^2 thereof, and it has at one end a head n whose outer face is provided with a diametral groove n^1 intersecting the bore of the tube N, into which groove the lugs h^1 depending from the tumbling-disk H are adapted to be entered upon lifting the tube N; but in order to render the manipulation of the tube N difficult, and so that instructed operators only can manipulate it, a pair of internal flanges n^2 , n^3 are formed in the inlet-tube i^2 ; said flanges being provided, respectively, with notches n^4 , n^5 with the notches of the flange n^2 at right-angles to those of the flange n^3 . The tube N has a pin n^6 secured thereto which projects therefrom at diametrically opposite points and when said tube is in normal position, the ends of said pin lie in a plane beneath the lower flange n^3 and at a right-angle to the notches n^5 therein, as best shown in Fig. 2.

The body of the intensifier is provided with a stuffing-box O at a point diametrically opposite the inlet-tube i^2 and through said stuffing-box the tube N slides. Secured to the lower end of tube N is a handle N^1 for rotating the same and held to said tube directly above the handle, is a cross-head N^2 to which are secured the lower ends of a pair of upstanding links N^3 lying on opposite sides of the tube N and the body of the intensifier. A handle P is provided for reciprocating the tube N; said handle having diverging arms p passing along opposite sides of the intensifier body and having one of their ends pivotally connected to bosses p^1 formed on opposite sides of said body, said arms being also pivotally connected between their ends to the links N^3 .

The tube N is provided with an air-escape opening R which is exposed when the said tube is in normal position, as shown in Fig. 2.

The operation of the device is as follows,—The intensifier is adapted for use only when the car-door is to be opened; at all other times it is removed from the car. When applying the intensifier for use, it is positioned with the outlet-tube i and the inlet-tube i^2 beneath the bushings E^1 and the valve-casing b, respectively; said bushing and valve-casing each acting as one member of a coupling. The other members of the couplings which are carried upon the tubes i and i^2 are engaged with their coöperating members to lock the intensifier in position without possibility of leakage of air or oil. After the coupling is attached, the handle N^1 at the lower end of the tube N is given a one-quarter turn to bring the pin n^6 of said tube in line with the notches n^5 in the lower flange n^3 so that upon grasping the handle P and raising the same, the tube is

elevated until the pin n^6 enters the space between the flange n^3 and the flange n^2 , as shown in Fig. 5. During this rotary movement of the tube N the groove n^1 in the head of said tube is brought in line with the lugs h^1 on the underside of the tumbling-disk H; and during the lifting of said tube, said lugs are caused to be entered in said groove, as shown in Fig. 5. It is then necessary to move the tube N through a one-quarter of a revolution in either direction to bring the pin n^6 in line with the notches n^4 in the flange n^2 and to bring the notch h^2 in the tumbling-disk in line with the lug b^4 in the valve-casing. Now upon lifting the handle P, the pin n^6 passes through the notches in the flange n^2 and the tumbling-disk H causing the disk G to be elevated and strike the lower end of the valve F for the purpose of unseating the latter, as shown in Fig. 6. The air under compression then passes through the valve-disk F, through the coil-spring G^1 , along the edges of the disk G and tumbling-disk H, through the inlet-tube i^2 and into the body of the intensifier, where it acts upon the piston K^2 and causes the oil or other liquid within the bore K to be forced out through the outlet-tube i and against the piston or movable body M for unlocking the car-door. When the locking-plunger m has been elevated by the piston M so as to disengage it from the coöperating-locking-elements of the car-door, the handle P is lowered to permit the disk G and the tumbling-disk H to become seated, whereupon the coil-spring b^3 in the cap of the valve-casing acts upon the valve F to seat the same. During the lowering movement of the tube N, the pin n^6 has passed through the notches n^4 in the flange n^2 and before the tube can be given a further downward movement, it must be turned to bring the pin n^6 in line with the notches n^5 in the flange n^3 . The handle P is then taken hold of to lower the tube N so as to cause the pin n^6 to pass through the notches n^5 , after which the tube is given a further one-quarter turn to bring the pin n^6 at right-angles to the notches n^5 , thus locking it against movement. The couplings J are then given a slight turn upon their respective tubes so as to free the interlocking parts thereof from those on the bushing E^1 and the valve-casing b, thus permitting the intensifier to be removed from the car. The air within the intensifier escapes through tube N and the opening R therein.

Having thus described my invention, what I claim is,—

1. An intensifier comprising a cylinder having an air-inlet tube and an outlet tube, and having also bores of two different diameters, pistons within said bores and arranged one to operate the other, a coupling member on said inlet-tube, a coupling mem-

- ber on said outlet-tube, and a valve operating device adapted to be operated by different movements to admit a power agent into the cylinder.
5. An intensifier comprising a cylinder having bores of different diameters and inlet and outlet tubes, a piston in each bore arranged one to operate the other, and a valve operating device extending through said cylinder.
10. 3. The combination with an air supply-pipe and an inlet-valve connected thereto, of an intensifier comprising a hollow body having a large bore at one end and a comparatively small bore at its other end, an inlet-tube communicating with the large bore of said body, an outlet-tube communicating with the small bore of said body, means for coupling said body to said inlet-valve, a piston within said large bore adapted to be actuated upon by compressed air introduced through said inlet-tube, a piston fitting within said small bore and rigidly connected to said first-mentioned piston,
15. 25. said last-mentioned piston serving to eject a fluid-body held within said small bore through said outlet tube, and means to open said inlet-valve to introduce air against said first-mentioned piston.
30. 4. The combination with an air-supply pipe and an inlet-valve connected thereto and normally in closed condition, of an intensifier coupled to said inlet-valve and having a small bore at one end and a large bore at its opposite end, pistons within said bores rigidly connected together, the smaller of said pistons acting to inject a fluid-body and force the same out of the intensifier and the larger piston being actuated by air introduced through said inlet-valve, a tube rotatable and slidable in said hollow-body adapted to manipulate parts of said inlet-valve, and a handle connecting said tube and adapted to cause the latter to slide.
35. 40. 45. 5. In an apparatus of the kind described, a valve comprising a casing, a spring-pressed valve within said casing and a tumbler-disk also within said casing adapted to be held against movement and prevent actuation of said valve, combined with a hollow cylindrical body having tubes at right-angles thereto, one of said tubes having connection with said inlet valve, said hollow body having bores of different diameters, a piston fitting in each of said bores and rigidly connected together, a tube extending diametrically through said hollow body and arranged for rotary and sliding movement, said tube being adapted to engage said tumbler-disk to rotate and elevate the same, and a handle connected to said tube to operate the same.
50. 55. 60. 65. 6. In an apparatus of the kind described, a valve comprising a casing, a spring-pressed valve within said casing, a tumbler-
- disk also within said casing adapted to be held against movement and prevent actuation of said valve, a lifting-disk between said valve and said tumbler-disk and a coil-spring between said disks, combined with a hollow cylindrical body having tubes at right-angles thereto, one of said tubes having connection, with said inlet-valve, said hollow body having bores of different diameters and corresponding pistons fitting therein and rigidly connected together, a tube extending diametrically through said hollow body and adapted for rotary and lengthwise movement, said tube being adapted to engage said tumbler-disk to rotate the same and elevate both disks to cause said valve to be opened, a handle on said tube for rotating the same, a pair of links connected to said tube and lying on opposite sides of said hollow body, and a swinging-handle pivotally connected at one end to said hollow body and having pivotal connection between its end to said links.
7. In an apparatus of the kind described, an inlet-valve comprising a valve-casing, a seat-disk threaded into said casing and provided with a central opening furnishing a valve-seat, a spring-pressed valve closing against said valve-seat, a tumbler-disk within said casing at the lower end thereof and normally held against movement, a lifting-disk interposed between said seat-disk and tumbler-disk and springs between said interposed disk and the tumbler-disk and seat-disk, combined with an intensifier coupled to said inlet-valve, a piston arranged for reciprocal movement within said intensifier, and means embodied in said intensifier for actuating said inlet-valve.
8. The combination with an air supply-pipe and an inlet-valve, of a hollow body having an inlet-tube at one end connected to said inlet-valve and an outlet-tube at its other end, said hollow body having bores of two different diameters and a pair of internal flanges in the tube connected with said inlet valve, said flanges having diametrical notches and the notches of one flange arranged at right-angles to those of the other, a piston within the larger bore of said hollow body adapted to be actuated by the air introduced from said supply-pipe, a piston within the smaller bore of said hollow body and rigidly connected with said first-mentioned piston, a tube arranged diametrically through said hollow body and having projections at diametrically opposite points adapted to be moved through the notches of said flanges, and a handle for manipulating said tube.
9. The combination with an air supply-pipe and an inlet-valve, of a hollow body having an inlet-tube at one end connected to said inlet-valve and an outlet-tube at its other end, said hollow-body having bores

of two different diameters, a piston within the larger bore of said body adapted to be actuated by the air introduced from said supply-pipe, a piston within the smaller bore of said body actuated by said first-mentioned piston, a rod arranged diametrically through said hollow body and adapted to actuate said inlet-valve, and means to prevent direct lengthwise movement of said rod.

10. The combination with an air supply-pipe and an inlet-valve, of a hollow body having an inlet-tube at one end connected to said inlet-valve and an outlet-tube at its other end, said hollow body having bores of two different diameters, a piston within the larger bore of said body adapted to be actuated by the air introduced from said supply-pipe, a piston within the smaller bore of said body and rigidly connected with said first-mentioned piston, a tube arranged diametrically through said hollow body and having an air escape opening permitting escape of air therethrough when said tube 25 is in normal position.

11. The combination with an air supply-pipe and a valve for controlling the escape of air therefrom, of an intensifier adapted to receive air from said pipe, and a valve 30 operating device for operating said valve embodying means to compel its being moved in different directions for opening said valve.

12. The combination with an air supply 35 pipe and a valve for controlling the escape of air therefrom, of a cylinder having bores of different diameters and having also an inlet-tube in connection with said air supply pipe and an outlet, a piston in each 40 bore arranged one to operate the other, and means to manipulate said valve, said means being operable only by movements in different directions.

13. In combination with a supply pipe 45 for the power-medium and a valve for controlling the escape of the power-medium therefrom, of an intensifier adapted to receive the power-medium from said supply-pipe, and means interposed between said

intensifier and said valve including tumbler mechanism to be operated before said valve can be opened.

14. In combination with a supply pipe for the power-medium and an intensifier, of means for admitting the power-medium to 55 said intensifier operable only by different movements.

15. A supply pipe for the power-medium and an intensifier coöperating therewith; combined with a valve controlling the escape of the power-medium from said supply pipe to said intensifier, and tumbler mechanism adapted to be operated to permit opening of said valve.

16. A supply pipe for the power-medium and an intensifier coöperating therewith; combined with a valve controlling the escape of the power-medium from said supply pipe to said intensifier, tumbler mechanism between said valve and said intensifier preventing the opening of said valve, and mechanism for operating said tumbler mechanism and cause said valve to open.

17. A supply pipe for the power-medium and an intensifier coöperating therewith; combined with a valve controlling the escape of the power-medium from said supply pipe to said intensifier, tumbler mechanism between said valve and said intensifier preventing the opening of said valve, and mechanism carried by said intensifier movable in different directions for operating said tumbler mechanism and cause said valve to open.

18. A supply pipe for the power-medium and an intensifier coöperating therewith; combined with a valve controlling the escape of the power-medium from said supply pipe to said intensifier, and tumbler mechanism including an operating rod for causing said valve to open.

In testimony whereof, I have affixed my signature in the presence of two subscribing witnesses.

WILLIAM J. MARTIN.
